United States Patent Office

Des. 188,046
Patented May 31, 1960

188,046

CHAIR

Ralph M. Galloway, 601 S. Audubon Ave., Tampa, Fla.

Filed Oct. 24, 1958, Ser. No. 53,149

Term of patent 14 years

(Cl. D15—1)

I claim:

The ornamental design for a chair, as shown.
